HIGHWAY CONSTRUCTION.

Application filed August 3, 1925. Serial No. 47,973.

The invention relates to the construction of highways more particularly designed for accommodating through traffic and it is the object of the invention to obtain a construction which provides an exclusive right of way for the fast traffic without interference either by cross traffic or traffic entering or leaving the highway.

It is a further object to provide an exclusive right of way for collective transportation including rail and road vehicles.

Further objects are to provide for separation of fast motor traffic from slow motor traffic with means for passing from the one to the other; to provide communication between the lanes for slow moving vehicles and the intersecting highways at one grade with an arrangement of the lanes for fast motor traffic and the rail traffic at a different non intersecting grade; to arrange rail stations at the elevated portions of the exclusive right of way where the opposite grades will assist in retarding the approaching cars and accelerating the departing cars; to provide completely protected under crossings for pedestrians and through which access may be obtained to the rail stations. With these and other objects in view the invention consists in the construction as hereinafter set forth.

In the drawings;

Figure 1 is a perspective view of our improved highway at a point of intersection with the crossing highway.

Figure 2 is a plan view.

Figure 3 is a cross section on the line 3-3 of Figure 2;

Figure 4 is a longitudinal section on the line 4-4 of Figure 2.

Heretofore highways have been constructed with a separation of grade at points of intersection with cross highways or railways. Such constructions only partially solve the problem of safeguarding the traffic for it is necessary to provide inter-communication between the crossing highways with the consequent danger of collisions at such points of inter-communication. It is the primary object of the present invention to avoid such danger by a construction in which the fast moving traffic and slow moving traffic are in separate parallel lanes. This permits of uninterrupted traffic in the fast moving lane while the slow moving lane provides for communication with the cross-

ing highway. There are also provided frequent points of inter-communication between the lanes through which a vehicle can pass from one to the other with perfect safety. Where there is a parallel railway this is preferably arranged between the high speed lanes and thus the cross traffic is thoroughly protected.

In detail A is the highway for exclusive right of way and B is a crossing highway. C are railway tracks which are arranged in the central portion of the highway A. D and D' are lanes for the high speed traffic which are adjacent to and on opposite sides of the tracks C. Preferably the tracks and high speed lanes are separated either by a row of trees or other means for lessening the danger of the unintentional passing of a vehicle from one to the other.

At points of intersection between the crossing highways the track C and high speed lanes D and D' are elevated while the intersecting highway is preferably correspondingly depressed. At the top of the elevation and over the intersecting highway there may be arranged stations E for the railways thereby taking advantage of the rise to check the momentum of a stopping car and the down-grade to accelerate a starting car. Furthermore, exits and entrance to the station may be by way of the tunnel beneath the elevated tracks and high speed lanes as indicated at F. Outside of and parallel to the high speed lanes are low speed lanes G, G' which are at the same grade as the high speed lanes D, D' excepting at intersection points of the crossing highways. Here the two lanes are separated the low speed lane declining downward to the grade of the crossing highway and providing inter-communication therewith. If desired, the high speed and low speed lanes may be separated by a grass plot or curbing cut away at frequent intervals for inter-communication between the two lanes.

With the construction described, the highways A may be used for the main thoroughfares and permit of high speed both for the rail traffic and the road traffic. At the same time, low speed traffic is accommodated and forms a safe intermediate avenue for passage from the high speed lanes to the intersecting highways.

What we claim as our invention is:

1. A highway construction comprising

- separate lanes for high speed and low speed traffic having frequent points of inter-communication, said lanes being separated in grade at crossing highways with the low speed lanes at the grade of the cross highway.
2. A highway comprising separate parallel lanes for high speed and low speed traffic having frequent points of inter-communication, a cross highway at the grade of the low speed lane at the points of intersection therewith and said high speed lane being elevated to pass over said intersecting highway.
3. A highway comprising parallel high speed and low speed lanes having frequent points of inter-communication and at the same grade for the greater part of their extent, a crossing highway at a lower grade than said first mentioned highway, downwardly inclined portions of said low speed lanes forming inter-communication with said crossing highway at the grade thereof and upwardly inclined portions of said high speed lanes for passing uninterruptedly over said crossing highway.
4. A highway comprising parallelly arranged rail tracks and roadways on opposite sides thereof and separated therefrom, said roadways being divided into parallel lanes for the high speed and low speed traffic with the high speed lanes adjacent to said tracks, an intersecting highway having grade communication with said low speed lanes, an elevated portion of said high speed lanes and tracks for separating the grade of the same from said intersecting highway, and a railway station at said elevated point.
5. A highway comprising parallelly arranged rail tracks and roadways on opposite sides thereof and separated therefrom, said roadways being divided into parallel lanes for the high speed and low speed traffic with the high speed lanes adjacent to said tracks, an intersecting highway having grade com-
- munication with said low speed lanes, an elevated portion of said high speed lanes and tracks for separating the grade of the same from said intersecting highway and a railway station at said elevated point and a tunnel communication with said station beneath said high speed lanes forming means of entrance and egress therefrom.
6. A highway comprising parallelly arranged rail tracks and roadways on opposite sides thereof and separated therefrom, said roadways being divided into parallel lanes for high speed and low speed traffic with the high speed lanes adjacent to said tracks, an intersecting highway having grade communication with said low speed lanes, an elevated portion of said high speed lanes and tracks for separating the grade of the same from said intersecting highway, a railway station at said elevated point, and means built into the supporting structure of said elevated portion providing communication between said railway station and the level of said intersecting highway.
7. A highway comprising high speed and low speed lanes having frequent points of inter-communication and at the same grade for a greater part of their extent, parallelly arranged rail tracks between said high speed lanes and separated therefrom a crossing highway at a lower grade than said first mentioned highway, downwardly inclined portions of said low speed lanes forming inter-communication with said crossing highway, and upwardly inclined portions of said high speed lanes and rail tracks for passing uninterruptedly over said crossing highway.
